UNITED STATES PATENT OFFICE.

CHARLES A. RICHARDS, OF CHICAGO, ILLINOIS.

PRINTING PRESS.

Application filed May 1, 1920. Serial No. 378,037.

To all whom it may concern:

Be it known that I, CHARLES A. RICHARDS, a citizen of the United States, residing at Chicago, in the county of Cook and State of Illinois, have invented certain new and useful Improvements in Printing Presses, of which the following is a specification.

This invention relates to printing presses. 10 It will be explained as applied to a multi-color press of the flat platen type.

One of the objects of the invention is to provide an improved multi-color printing press.

15 Another object is to provide a multi-color press which will be reliable in operation, and easy to adjust and maintain.

Another object is to provide a multi-color press with an improved fountain construction.

20 Another object is to provide a multi-color press with improved and reliable color distribution.

Another object is to provide a press 25 wherein the ink fountains may be readily applied and removed in sets.

Another object is to provide a multi-color press wherein each impression will be of the same depth of color throughout.

30 Another object is to provide a multi-color attachment which may be applied to ordinary printing presses.

Other objects and advantages of the invention will appear from the specification 35 and claims.

An embodiment of the invention is illustrated in the accompanying drawing, in which:—

Fig. 1 is a side elevation of the press. 40 Fig. 2 is a section on the line 2—2 of Fig. 1.

Fig. 3 is an enlarged elevation of the side of the press opposite that shown in Fig. 1.

Fig. 4 is an enlarged section on the line 45 4—4 of Fig. 2.

Fig. 5 is an enlarged section on the line 5—5 of Fig. 1.

Fig. 6 is a section on the line 6—6 of Fig. 5.

50 Fig. 7 is an enlarged section on the line 7—7 of Fig. 1.

Fig. 8 is an enlarged partial section on the line 8—8 of Fig. 1.

Fig. 9 is a detailed view of part of the 55 fountain roller operating mechanism moved

to the back of the press frame in position for removal.

Fig. 10 is a vertical section thru an ink fountain.

Fig. 11 is a section on the line 11—11 of 60 Fig. 1.

Fig. 12 is a section on the line 12—12 of Fig. 9, and

Fig. 13 is a perspective of a color selecting cam section such as used on the printing 65 chase.

The press comprises, in general, a pedestal A, a printing frame B, carrying the chase of forms to be printed, a reciprocating platen C for pressing the paper or other 70 material against the forms and an ink distributing system D for holding and conveying the ink to the forms.

The press is operated thru a main shaft 15 which is rotated by any suitable source 75 of power belted to a pulley 16 carried by the shaft. Shaft 15 has a pinion 17 mounted thereon which engages a gear wheel 18 carried on one end of a shaft 19. Shaft 19 has upon its other end a cam 20. The operation of platen C and the ink distributing 80 system D are brought about by the rotation of gear wheel 18 and cam 20 as will be hereinafter described.

Platen.

85

Platen C is pivotally carried upon the outer end of a pair of connecting rods or links 21 and 22. The inner end of link 21 is pivoted to a stud 23 projecting from the 90 face of cam 20 eccentrically of shaft 19. In a similar manner the end of link 22 is pivoted to a stud 24 projecting from the face of gear wheel 18 eccentrically of shaft 19. Thus when gear wheel 18, shaft 19 and cam 20 are rotated, platen C is reciprocated from the dotted line position of Fig. 1 away from the printing frame or chase to the full line position of Fig. 1 against the printing frame or chase. In the latter position, the 95 paper or other material carried on the face of the platen is pressed against the printing forms carried by the chase, and the desired impressions are made.

100

105

The ink distributing system.

Ink fountain sets.—The ink fountains in which the vari-colored inks are stored, are arranged in horizontal or transverse rows 110

or sets. The sets are bodily adjustable and removable from the press and each fountain of a set is independently adjustable to govern the supply of ink.

- 5 In the press chosen for illustration, there are four sets of fountains 30, 31, 32 and 33 arranged one beneath the other. Each set comprises six individual fountains. This particular press thus provides for a maximum of twenty-four different colors or shades. Presses may be constructed for greater or lesser maximum numbers of colors or shades by increasing or decreasing the number of sets of fountains or the number 10 of fountains per set or both.

Since the sets of fountains and the individual fountains are all alike, only one set and one fountain will be described.

- As shown in Figure 8, a set of fountains 20 comprises a casing or frame with opposite end walls 34 and a back and bottom wall 35. The casing also has removable intermediate walls 36 separating the individual fountains. End walls 34 are positioned in between pairs of guides 37. Guides 37 project inwardly from the edges of opposite sides of horizontally disposed slots 38 in the opposite sides of the upper press frame 39. The forward ends of end walls 34 provide bearings 25 for a shaft 40 upon which is mounted the fountain rollers 41. Fountain rollers 41 are feathered to shafts 40 so that they may be axially moved thereon and rotated thereby. Into the rear edges of end walls 34 are 30 threaded adjustable locking screws 45. Each screw 45 has a dog 46 loosely mounted thereon and adapted to be held in any desired position between lock nuts 47. Dogs 46 co-operate with notches 48 in guides 37 to retain the sets of fountains in proper position. Each set, as an entirety, may be moved back 35 between guides 37 for cleaning, reinking, etc., or may be removed from the press bodily by turning dogs 46 out of notches 48. The fountain roller sets being carried by the fountain frames or castings keep the fountains intact during this backward movement or removal. The position of a set in the press may be readily varied by changing the 40 position of a dog 46 upon corresponding screw 45.

Ink fountains.—A fountain comprises a trough-shaped compartment, the forward side of which is formed by a fountain roller 41. The fountain rollers may be made of suitable metal. The bottom of a fountain is formed of a resilient plate 50. Plate 50 may be made of a thin sheet of spring steel or other suitable material. The rear edge 45 or heel of plate 50 is spaced from wall 35 by a block 51 and is secured thereto by set screws 52. The forward edge or toe of each plate 50 is in close proximity to or in contact with the corresponding fountain roller 41.

The fountain roller is rotated in the direction of the arrow, as will be hereinafter described, to convey ink from the fountain, and plate 50 acts as a valve to control the flow or quantity of ink conveyed to the 70 ductor rollers, to be hereinafter described.

The relation between each fountain roller 41 and corresponding plate 50 is controlled by an adjusting screw 52'. Screw 52' passes through a threaded hole in wall 35 and its 75 forward end engages plate 50. Threading screw 52' forward presses the toe of plate 50 closer to or against roller 41, whereby less ink is conveyed from the fountain. Threading screw 52' rearwardly allows the toe of 80 plate 50 to separate a greater distance from roller 41 allowing a greater amount of ink to be delivered from the fountain.

In the press illustrated there are therefore twenty-four independently adjustable inking 85 fountains and a corresponding number of inking rollers or inking roller sections. The fountains and inking rollers are grouped in four rows or sets of six fountains or rollers each.

The removable intermediate walls of the fountains and the feathered mounting of the fountain rollers on their respective shafts allow the width of colors to be increased as desired. To provide a wider color impression, it is only necessary to remove one or more of the intermediate walls to increase the size of a fountain and to slide together the corresponding fountain rollers.

Rotation of fountain rollers.—In order to 100 facilitate the removal of ink from the fountains and the even distribution thereof to the ductor rollers to be hereinafter described, the fountain rollers are positively rotated at the proper time. The amount of this rotation can be varied at will or rotation may be stopped altogether, as will be hereinafter described.

Each fountain roller shaft 40 is provided with a ratchet wheel 55 at one end thereof. 110 Each shaft 40 also has pivotally mounted thereon a ratchet lever 56. Each ratchet lever 56 carries a pawl 57 pivoted and secured thereto by a bolt 58. A biasing spring 59 maintains pawl 57 in yielding engagement with ratchet wheel 55. When the outer end of lever 56 is raised, pawl 57 passes inactively over ratchet wheel 55, but when the outer end of lever 56 is lowered, the pawl turns ratchet wheel 55, and consequently the corresponding fountain rollers, 120 in the direction of the arrow.

All of the levers 56 of the several fountain rollers are linked to an oscillating bar 61 by pin and slot connections 62. Bar 61 125 is carried upon the outer end of two levers 63, being pivotally secured thereto by bolts 64. Levers 63 are pivotally secured to the frame at their inner ends, by bolts 65. The lower lever 63 has a link or connecting rod 130

67 pivoted to its outer end. Connecting rod 67 has an adjustable collar 68 and is surrounded by a coiled spring 69. Rod 67 also has an adjustable collar 75 and passes loosely through an arm 76 pivotally carried upon a reciprocating counter weight 77.

Counter weight 77 balances the reciprocating form roller carriage to be hereinafter described. Counter weight 77 is connected to and carried by a shaft 78 through an arm 79. Shaft 78 carries adjacent one end a bifurcated crank 80. Crank 80 has a pin 81 interconnecting its bifurcated end and this pin may be positioned within the open slot 82 of a lever 83. Lever 83 is pivotally connected to one arm of a bell crank lever 84 by a pivot pin 85. Bell crank lever 84 is carried by a stud shaft 86 projecting from the pedestal of the press. The other arm of lever 84 has a pair of cam rollers 87 positioned within a cam groove 88 in the inside face of gear wheel 18. Cam groove 88 is formed so that the rotation of wheel 18 causes lever 83 to oscillate and, when pin 81 is within the bottom or closed end of slot 82 as shown in Fig. 1 the form roller carriage, to be hereinafter described, and its counter weight 77 are oscillated. The oscillation of counter weight 77 raises and lowers rod 67 and the outer end of lever 63 and consequently intermittently rotates the fountain rollers. The cams are so positioned that the fountain rollers are rotated while they are engaged by the ductor rollers.

The effect of the oscillation of counter weight 77 upon the fountain rollers and consequently the amount of rotation of the fountain rollers for each reciprocation of the counter weight may be varied by changing the positions of collars 68 and 75. Thus each oscillation of counter weight 77 may rotate the fountain roller shafts the equivalent of one or several teeth of ratchet wheels 55 as desired.

The press is provided with a trip lever 89 which cooperates with a horn or cam 90 extending from lever 83 to control the oscillation of shaft 78. Under ordinary operating conditions, lever 89 is in such position that pin 81 is locked in slot 82 as shown in Fig. 1. Then the form roller carriage and counter weight are oscillated and the fountain rollers are intermittently and positively rotated as previously described.

Moving lever 89 to its other position causes it to engage cam 90 elevating the free end of lever 83. The opening in slot 82 is then brought into register with pin 81 and the oscillation of lever 83 through cam groove 88 and cam rollers 87 is no longer communicated to crank 80 and shaft 78, because the opening in slot 80 of lever 83 permits the lever to move back and forth without carrying pin 81 with it. Consequently the oscillation of the form roller carriage

and the rotation of the fountain rollers ceases.

This is of considerable advantage as inking ceases when the printing stops and excess of colors do not accumulate in the ink distributing system.

The enlargements at the rear ends of slots 38 allow the ratchet wheels 55 and ratchet levers 56 to be passed therethrough when a set of fountains is to be removed from the press. The fountain sets may thus be removed readily for cleaning and repair.

Ductor rollers.—Associated with each fountain set is a ductor roller 95 for transferring the ink from the fountain rollers to the vibrator rollers hereinafter described, of a corresponding set. There are consequently four ductor rollers 95. The ductor rollers are preferably of rubber or suitable composition.

Each ductor roller 95 is provided with a shaft 96. The opposite ends of shaft 96 are individually journaled in small brackets 97. Brackets 97 are provided with threaded holes for receiving set screws 98 which pass through the two ends 99 of a ductor frame. The top and bottom of the ductor frame are formed of rods 100 and 101 secured at their ends to the opposite end frames 99. The ductor frame thus carries all of the ductor rollers and each roller is independently adjustable at both ends. This adjustability is accomplished by the set screws 98. When the set screws are loosened, the corresponding brackets 97 may be rotated thereabout. When the set screws are tightened, the corresponding bracket is clamped in position against the end of the ductor frame.

The ductor frame as a whole is capable of being oscillated so that the ductor rollers are moved into and out of engagement with the fountain rollers and the vibrator rollers to be hereinafter described.

Each end 99 of the ductor frame is provided with a pair of hollow studs 105. Into the holes of each stud 105 extends the end of a screw 106 threaded through one arm of a bell crank lever 107. The two upper bell crank levers, one on each side of the press, are pivoted on studs 108 at the respective sides of press frame 39. The two lower bell crank levers 107, one on each side of the press, are carried by and secured to a shaft 109. Shaft 109 is journaled in suitable bearings in press frame 39. The bell crank levers on each side of the press are joined, to operate together, by a link 110.

Secured to shaft 109 is a lever 115 carrying a cam roller 116. Cam roller 116 rides upon the surface of cam 20 and reciprocates shaft 109, levers 107 and the entire ductor frame in accordance with the high and low portions of the cam. A coiled spring 117 maintains cam roller 116 under pressure upon the surface of cam 20.

The ductor frame is moved by the force of cam 20 into the position wherein the ductor rollers engage the fountain rollers. The return of the ductor frame is assisted by a coiled spring 118 which is secured at one end to one arm of one of the lower ductor frame levers 107 and at its other end to press frame 39.

Thus as cam 20 is rotated from the power shaft, the ductor frame is oscillated forth and back so that the ductor rollers alternately engage the fountain rollers and the vibrator rollers.

Vibrator rollers.—In front of the ductor rollers, in a position to be engaged thereby during the forward movement of the ductor frame, are positioned a plurality of vibrator rollers 125. These rollers may be made of steel or other suitable material.

Vibrator rollers or roller sections 125 are arranged in sets corresponding to the sets of fountains and each set has as many rollers or sections as there are fountains in a set. For the press illustrated, there are, therefore, four sets of vibrator rollers, each set consisting of six rollers or sections. The rollers or sections are adjustably secured to their respective shafts by set screws or other suitable means.

Each set of vibrator rollers is mounted upon a shaft 126. The projecting ends of shaft 126 are individually journaled in independent bearing blocks 127. Blocks 127 are vertically grooved on both their front and back sides to accommodate and form ways for a pair of guides 128 formed in uprights of press frame 39. The lower blocks, on each side of the press, rest on projections 129 and the stacks or tiers of bearing block are retained and securely held in position by screws 130.

The vertical position of each set of vibrator rollers is independently adjustable on both sides. This may be readily accomplished by inserting or removing small wedges or shims between the bearing blocks whose adjustment is desired.

Vibration of vibrator rollers.—In order to facilitate the even distribution of ink both to and from the vibrator rollers, these rollers are given a slight, positive, longitudinal or axial to and fro movement called "vibration".

Gear wheel 18 drives a pinion 135 secured to a shaft 136. Shaft 136 extends across the press and is journaled in suitable bearings in press frame 39. Near one end within the press frame, shaft 136 carries a worm 137. Worm 137 engages a worm wheel 138 journaled on a stud carried by a bracket 139 secured to press frame 39. Pivoted to worm wheel 138 eccentrically of its axis is a connecting rod 140. The other end of rod 140 is pivotally connected to a plunger 141 extending through one of the uprights of press

frame 39. The outer end of plunger 141 carries a toggle block 142. The extent of the reciprocation of plunger 141 may be varied to regulate the amount of vibration by changing the eccentricity of connecting rod 140 relative to worm wheel 138. This is accomplished through an adjustable bolt 143.

Journalled on a pair of studs 144 and 145 projecting rearwardly from the front of press frame 39, are toggle levers 146 and 147, respectively. Each lever 146 and 147 has a pair of grooved lugs 148. The grooves in lugs 148 fit over collars 149 secured to the respective vibrator roller shafts 126. The toggle levers are also provided with a cooperating tongue and slot connection 150 for communicating motion between them. A similar tongue and slot connection 151 is provided between toggle lever 146 and toggle block 142.

When plunger 141 is reciprocated by the rotation of gear wheel 135, shaft 136 and worm wheel 138, toggle lever 146 is oscillated about its pivot 144. The oscillation of lever 146, through grooved lugs 148 and collars 150, alternately forces the two lower vibrator roller shafts 126 in and out. The oscillation of lever 146 also causes the oscillation of toggle lever 147 about its pivot 145. The oscillation of lever 147 produces a similar alternate in and out movement or vibration of the two upper vibrator roller shafts. Thus the longitudinal or axial movement is positively communicated to the vibrator rollers and their movement is rendered more exact and reliable. This is of importance in multi-color work where blending or mixing of the colors must be prevented.

Rotation of vibrator rollers.—The vibrator rollers are also positively rotated. Shaft 136 has secured thereto a sprocket wheel 155. A second sprocket wheel 156 is mounted on a stud shaft carried by an adjustable block 157 positioned in a small closed, rectangular slot 158 in press frame 39. An adjusting screw 159 threads into block 157 to vary the position thereof for regulating the distance between sprocket wheels 155 and 156.

A chain 160 passes over sprocket wheels 155 and 156 and meshes with sprocket wheels 161 feathered on the end of the vibrator roller shafts 126. Thus the rotation of shaft 136, in addition to vibrating the vibrator rollers 125, positively rotates the same. The feathered connections between shafts 126 and sprocket wheels 161, allow the shafts to be rotated, while at the same time there is no interference with their axial movement. A plate 162 maintains chain 160 in operative position relative to sprocket wheels 161.

Intermediate rollers.—In front of each set of vibrator rollers to transfer the ink therefrom is an intermediate roller 165. Intermediate rollers 165 are preferably of suitable

composition and are provided with shafts 166. The opposite ends of shafts 166 are individually carried in a small bracket 167. Brackets 167 are secured to the ends 168 of an intermediate roller frame by screws 169. The intermediate roller frame is completed by top and bottom rods 170 and forms a unit in which all of the intermediate rollers are carried. The opposite ends of each intermediate roller are individually adjustable by turning the corresponding bracket 169 about its screw 169. Tightening the screw then clamps the bracket and roller in position. The intermediate roller frame is held in suitable guide ways 171 on opposite sides of press frame 39.

Front rollers.—Located in front of and in contact with each intermediate roller is a set of front rollers or sections 175. Each set 20 comprises as many rollers or sections as there are fountains in a corresponding set. In the press illustrated there are consequently four sets of front rollers of six individual rollers or sections. The rollers of each set 25 are adjustably mounted together on a shaft 176, being secured thereto by set screws or other suitable means. The front rollers are of steel or other suitable material.

One end of each of the shafts 176 is held 30 in an individual thrust bearing projecting from one side of press frame 39. The other end of each shaft 176 has a tongue 177 which extends into a socket 178 carried by the end of a stud shaft 179. Shafts 179 are journaled in the side of press frame 39 and each 35 is provided with the sprocket wheel 180. Sprocket wheels 180 are engaged and rotated by chain 160. A plate 181 presses chain 160 into operative relation to sprocket 40 wheels 180.

Thus the front rollers are positively rotated to facilitate the transfer of ink from the vibrator rollers to the form rollers.

Form rollers.—The inks as taken from 45 the front rollers are selectively applied to the printing forms by form rollers 190. These rollers are preferably of composition and there is one roller for each set of fountains. Form rollers 190 are provided with 50 shafts 191 which are journaled at opposite ends in individual bearing blocks 192. Bearing blocks 192 are slidably mounted in recesses in the side frames 193 of a form roller carriage 194. Each block has a pin 55 195 extending rearwardly thru an opening in the carriage.

A spring 196 surrounding each pin 195 biases the respective blocks 192 toward the bottom of the recesses in the carriage side 60 frames.

Form roller carriage 194 is provided on its opposite sides with guide tongues 200 which are adapted to slide in suitable ways in the press frame 39.

The carriage has pivotally connected to 65 its opposite side frames a pair of links 201. Links 201 are each pivotally connected to a crank 202. Cranks 202 are rigidly fastened to opposite ends of shaft 78.

Therefore as shaft 78 is oscillated as hereinbefore described, the form roller carriage is moved up and down alternately in front of the front rollers and the printing form or chase.

Color selecting by form rollers.—Each 75 form roller shaft 191 is provided on each end with a pair of collars or rollers 205 and 206. The outer pair of rollers 206 of all of the front roller shafts are in alignment, the inner pairs of rollers 205 are longitudinally 80 adjustable on their respective shafts 191.

Rollers 205 cooperate with suitable cams on the front face of press frame 39 to cause the selective engagement of the necessary sets of form and front rollers properly to 85 remove the desired colors.

Secured to the front face of press frame 39 and acting as one wall of the housing for front roller sprocket wheels 180 are a pair of cam plates 210. Cam plates 210, one 90 on each side of the press frame, are provided with corresponding pairs of cams or roller elevating runways 211, 212 and 213. These cams, in the press illustrated, are in alignment with rollers 205 of the top, next to the top and third form rollers respectively, and slope outwardly from top to bottom as clearly shown in Fig. 4. The lowermost part of both sloping cams of a pair are in such a position relative to the form rollers that, as the form roller carriage travels upward, the form rollers selectively approach and engage the proper sets of front rollers. Thus the top form roller is held away from the front rollers by the high 95 surfaces of plates 210 until rollers 205 thereon meet cams 211. Thereupon during the remainder of the upward travel of carriage 194 the force of springs 196 of the upper form rollers gradually force blocks 192 rearwardly, carrying the form rollers with them and causing the upper form rollers to engage the upper set of front rollers.

In a similar manner the next-to-the-top form roller is held away from the two lower sets of front rollers, as the carriage moves upwardly, but is caused to engage the next-to-the-top front roller set. So also the third form roller engages only the third front roller set and the bottom form roller engages only the bottom front roller set.

In this manner each form roller carries only the colors or shades of the corresponding set of inking fountains. The entire circumferential surface of a given portion of each form roller, as in the case of all of the other rollers of the press, therefore is confined to a single color or shade. There is 125

consequently no opportunity for and no danger of circumferential or longitudinal overlapping of the colors.

When the form roller carriage passes downwardly it moves over the printing frame so that the form rollers may selectively transfer the colors and shades to the printing forms as will hereinafter be described.

10

Printing frame.

The printing frame B comprises a rectangular frame or chase 215 detachably secured to the press and in which the various forms 15 216 to be printed are "locked up" in the usual manner. In the press illustrated, these forms are shown as rectangular blocks for producing impressions arranged in the manner of the ordinary paint card or chart 20 for showing samples of paint colors. With the arrangement shown forty-eight rectangles or blocks are provided to produce twenty-four different colors or shades in duplicate on one impression of the press. The 25 colors are arranged in two groups of six horizontal or transverse rows and four vertical or longitudinal rows. Any lesser number of colors can be printed on the press by simply locking up the chase with a lesser 30 number of printing forms. The capacity of presses can be varied by changing the number of individual and sets of fountains and ink distributing rollers as previously explained. The printing forms may take various shapes, sizes and arrangements as 35 desired.

Color selection of printing frame.—The 40 form rollers as they pass over the printing frame are selectively brought into engagement with the printing forms or blocks of the chase to transfer the colored inks thereto.

On opposite sides of the chase 215 are duplicate sets of cam tracks for cooperation 45 with the selecting rollers 205 of the form rollers. These cam tracks may be made up in various ways. They may be composed of cam track sections 217 such as that illustrated in Fig. 13. The sections being 50 formed in various lengths and being assembled on the chase in various combinations, allow a ready means of setting up or arranging for the selective operation of the form rollers at the same time as the setting up of the printing forms. The cam sections 55 are secured to chase 215 by suitable screws passing thru holes 218. The screws thread into wedge shaped nuts which may be adjustably positioned in grooves in the chase. When the screws are turned the nuts wedge 60 into the grooves to hold the cam tracks firmly in position.

The high or elevated portions of the cam sections, when engaged by rollers 205, maintain a form roller far enough away from the chase to prevent the roller engaging the

printing forms. On the other hand the sloping portions of two abutting cam sections allow the force of springs 196 to cause the form rollers to approach the printing frame and finally reach a position to strike 70 the printing forms. Thus as the form roller carriage passes to its lowermost position, the form rollers are selectively brought into contacting relation to horizontal or transverse rows of printing forms and, because 75 of this engagement, the continuing downward movement of the form roller carriage causes the form rollers to be rotated upon the forms to evenly apply the ink over the 80 entire surface thereof. This rotation of the form rollers over the surface of the printing forms is produced by the engagement of the outer rollers 206 of a depressed form roller and the tracks 219 on the outer edges 85 of the printing frame.

In the press illustrated the low portions 90 of the inside cam tracks upon which ride the selecting rollers 205 of the bottom form roller are designated 220. These low portions are in horizontal alignment with the fourth and eighth rows of printing forms. In consequence, as the form roller carriage passes downwardly over the printing frame, the colors carried by the bottom form roller are transferred to the printing forms of 95 both the fourth and eighth rows of forms. In a similar manner the low portions 221 of the second cam tracks cause the colors of the next to the bottom form roller to be transferred to the third and seventh rows 100 of forms. Likewise the colors of the top form roller are transferred to the first and fifth rows of forms and the colors of the next to the top form roller are transferred to the second and sixth rows of forms. 105

The first four horizontal rows of forms may thus impress twenty-four different colors or shades and the lower four rows, a duplicate set of colors at one impression of the press. Every form in each row, either laterally or longitudinally, may print a different color or shade.

In order to prevent the form rollers from passing over their respective rows of forms during both the downward and upward travel of the form roller carriage, the form rollers are lifted clear of the cam tracks on the upward travel of the carriage. This prevents the production of so-called "ghosts" or two depths of color on the same form.

Pivoted to each side frame 193 of the form roller carriage are a pair of levers 222 and 223. Connecting bars 224, pivotally connected to the inner ends of levers 222 and 223, bear against the backs of form roller shaft bearing blocks 192. By rocking either of levers 122 or 123 the operator may force all of the form rollers away from the forms against the pressure of 125 springs 196. This is also accomplished au- 130

tomatically during the reciprocation of the form roller carriage.

A lever 225 pivoted to roller carriage frame 193 by a pivot 226 carries a roller 227. Roller 227 bears against bar 224. Lever 225 during the downward motion of the form roller carriage engages an arm 228 secured to the frame of the press. Arm 228, after the forms have been properly inked, causes lever 225 to push bars 224 outwardly moving all of the form rollers out of the plane of any of the forms or front rollers. Roller 227 drops into a small notch in bar 224 so that lever 225 and the form rollers are maintained in this position until the form roller carriage is again in front of the front rollers. During the upward movement of the form roller carriage lever 225 engages a stop 230 secured to press frame 39. Thereupon the lever is depressed and springs 196 force their respective form rollers rearwardly where the rollers on the front roller shafts engage the cams on the press frame and the front rollers may be selectively brought into contact with the front rollers.

Summary of operation.

Summarized briefly, the operation of the press is as follows:

The rotation of main drive shaft 15 rotates gear wheel 18 and cam 20. The rotation of gear wheel 18 drives shaft 136 which, through chain 160, rotates the vibrator rollers 125 and the front rollers 175 and, through worm 137, worm wheel 188, connecting rod 140, plunger 141 and the toggle levers 145 and 146, moves the vibrator rollers transversely of their axes. The rotation of gear wheel 18, through the cam in the face thereof, also causes form roller carriage 194 to move up where the form rollers 190 engage the front rollers and down where the form rollers may engage the printing forms 216. In the upward movement, the form roller sets are selectively brought into contact with the proper front roller sets. As the form rollers pass over the printing forms, the form roller sets are selectively brought into engagement with the proper sets or transverse rows of forms. The cam in the face of gear wheel 18, through weight 77 and connecting rod 67 and the levers associated therewith, also causes the positive rotation of the fountain rollers. This rotation is intermittent and is so timed that it takes place while the fountain rollers and the ductor rollers are in contact. The rotation of gear wheel 18 and cam 20 through links 21 move the platen to and from printing position. The operation of the platen and form roller carriage is so timed that the platen is against the paper while the form rollers are up collecting ink

from the front rollers and is against its back stop, for the reception of the material to be printed upon when the form rollers are down imparting their ink to the printing forms.

Cam 20, through levers 115, 106 and 107, also oscillates the ductor frame so that the ductor rollers are alternately moved into engagement with the fountain rollers and the vibrator rollers.

The ink distributing and color selecting mechanism is so mounted on the press and is so constructed, that it may be applied readily to ordinary platen presses. The individual and collective adjustment, insertion and removal of the inking fountains is readily accomplished and the colors are distributed and applied and kept absolutely separated. The number and arrangement of colors up to the maximum of any given press may be varied at will. Each row of printing forms either laterally or longitudinally may print as many different colors as there are fountains in a given row.

Having described my invention what I claim as new and desire to secure by Letters Patent is:—

1. A multi-color printing press attachment having a supporting framework, provided with guide-ways, a plurality of ink fountain frames movably mounted in and removable from the guide-ways of the supporting framework, a set of individual ink fountains adjustably mounted on each fountain frame, said fountains having adjustable sections for closing each fountain and permitting ink to be taken therefrom, a printing frame in which forms may be set to correspond to the fountains, and means for selectively applying inks from the fountains to forms in the frame.

2. A multi-color printing press attachment having a supporting framework, a plurality of ink fountain frames individually adjustable and removable from the framework, a set of individual ink fountains adjustably mounted on each ink fountain frame, said fountains comprising a sectioned ink conveying roller mounted on each ink fountain frame and for taking inks from the fountains thereof, a ductor roller frame movable toward and away from the fountains, a ductor roller for each set of fountains and adjustably carried by the ductor frame, an axially oscillating vibrator roller for each set of fountains and engageable by the ductor rollers, a front roller for each set of fountains, an intermediate roller between each vibrator roller and the corresponding front roller, means for positively rotating the vibrator rollers and front rollers, a frame for holding printing forms in sets corresponding to the sets of fountains, a form roller carriage movable alternately over the front rollers and the forms, se-

- lectable form rollers carried by the form roller carriage, selecting means for selectively effecting engagement between certain form rollers and certain sets of forms, and
- 5 means for preventing engagement between form and front rollers when the form roller carriage moves in one direction.
3. A multi-color printing press having a frame for holding printing frames in prearranged sets, a plurality of ink fountain frames for carrying sets of fountains corresponding to the form sets, a fountain roller for each set of fountains and carried by the corresponding fountain frame, a
- 10 ratchet movement for rotating each fountain roller, means whereby each fountain frame may be independently adjusted and removed, and selectively operated ink distributing means for conveying inks from
- 15 certain fountains to corresponding sets of forms.
4. A printing press having a printing frame for holding forms in sets to be printed, a reciprocatable form roller for each set of forms, an independent ink distributing roller for conveying ink to each form roller, means for selectively bringing each form roller alternately into contact with its corresponding distributing roller and set of
- 25 forms, and means for preventing contact between the form rollers and corresponding distributing rollers during the movement of the form rollers in one direction.
5. A printing press having a press frame, a plurality of ink fountains arranged in sets, a casing for holding a set of fountains and adjustably and removably held in said frame, a fountain roller journaled in said casing and movable therewith, a printing frame, a form roller, a form roller carriage adapted to be reciprocated to and from said frame, means for reciprocating said carriage, operative connections between said means and said fountain roller to rotate the fountain roller to convey ink from said fountains, and ink distributing rollers between said fountain roller and said form roller.
6. A printing press having a printing frame for holding forms to be printed, inking rollers for inking forms held by said frame, a plurality of ink fountains arranged in a set, a removable casing for holding the set of said fountains as a unit, a fountain roller forming one wall of the fountains and journaled in said casing to be movable therewith and means for independently adjusting the relation between each fountain and said fountain roller for regulating the quantity of ink conveyed by said fountain roller from a fountain to said inking rollers.
7. A printing press having a plurality of fountains arranged in a plurality of sets, an independent casing for holding the foun-
- tails of each set, a fountain roller journaled in each casing and forming a part of the fountains held thereby to convey the ink therefrom, a printing frame for carrying forms to be printed, a plurality of form rollers, one for each fountain set, a carriage for movably carrying said form rollers, means for moving said carriage to and from said printing frame, and adjustable operative connections between said means and said fountain rollers for adjustably and positively rotating said fountain rollers.
8. A printing press having a plurality of sets of ink fountains, a fountain roller for each set of fountains, a continuous ductor roller for each fountain roller, a pivotally mounted ductor frame carrying all of said ductor rollers in independently adjustable relation and moving the same into and out of contact with said fountain rollers, a printing frame for holding forms to be printed, and sets of ink distributing rollers for conveying ink from said ductor rollers to the forms held by said frame.
9. A printing press having sets of ink fountains, a ductor roller pivotally mounted to move into and out of ink collecting position relative to each set of fountains, a printing platen, means for reciprocating said platen, a vibrator roller in position to be engaged by each ductor roller, and a driving connection between said means and said vibrator rollers to rotate and axially vibrate the same.
10. A printing press having a plurality of sets of ink fountains, a ductor roller pivotally mounted to move into and out of ink collecting position relative to each set of fountains, a printing frame for holding forms to be printed, means for impressing the material to be printed against the forms in said frame, power operating mechanism for operating said means and reciprocating said ductor rollers, a vibrator roller in position to be engaged by each ductor roller during the reciprocation thereof, adjustable connections between said means and said vibrator rollers for moving said vibrator rollers axially and varying the axial movement thereof, and ink distributing rollers for conveying ink from said vibrator roller to the forms in said frame.
11. A printing press having a plurality of sets of ink fountains, a ductor roller for each set of said fountains, a vibrator roller for each ductor roller to take ink therefrom, means for axially moving one of said vibrator rollers, connections between said vibrator rollers for communicating the axial movement therebetween, a printing frame for holding forms to be printed, means for pressing the material to be printed against said forms, and ink distributing rollers for conveying ink from said vibrator rollers to the forms.

12. A printing press having a printing frame for holding printing forms, a plurality of form rollers, means for reciprocating said form rollers across said frame to convey ink to the forms therein, a set of ink fountains for each form roller, a fountain roller for each set of fountains for conveying ink from said fountains, a vibrator roller for each form roller and positively moved in an axial direction through the action of said means, a ductor roller for each form roller and reciprocable alternately into contact with said vibrator rollers and said fountain rollers, and operative connections between said means and said fountain rollers to cause positive relative movement between said ductor rollers and said fountain rollers when the same are in contact.
13. A multi-color printing press having a platen, driving mechanism therefor, a printing frame for receiving a chase upon which printing forms are set, a plurality of sets of ink fountains, a plurality of sets of fountain rollers, a ductor frame supporting a plurality of sets of ductor rollers, a plurality of vibrator rollers there being one vibrator roller for each set of fountain rollers, vibrator mechanism operated by said platen driving mechanism and acting to positively move said vibrator rollers alternately in opposite directions axially, means operated by said platen driving mechanism for oscillating said ductor frame to cause said ductor rollers to alternately engage said fountain rollers and said vibrator rollers, operative connections between said platen driving mechanism and said fountain rollers to rotate said fountain rollers when the same are engaged by said ductor rollers, a plurality of sets of front rollers, positively driven sets of ink distributing rollers between said vibrator rollers and said front rollers to convey the ink between corresponding sets thereof, a form roller carriage movable alternately to a position in front of said printing frame and said front rollers, a plurality of form rollers carried by said carriage there being one form roller for each set of fountains, cams for selectively causing the engagement of front and form rollers when the carriage is in front of the front rollers, and cams for selectively causing the engagement of form rollers and forms set in the printing frame when said carriage is in front thereof.
14. A printing press having a plurality of ink fountains for holding inks of different colors, said fountains being arranged in independently adjustable sets, a plurality of fountain rollers arranged in sets corresponding to the sets of fountains and for conveying the inks therefrom, a ductor frame, sets of ductor rollers carried by said frame and corresponding to the sets of fountains, a vibrator roller for each fountain and arranged in corresponding sets, sets of intermediate rollers corresponding to the sets of fountains, a form roller for each set of fountains, a carriage for carrying and reciprocating said form rollers to and from said intermediate rollers, a printing frame for carrying forms to be printed and over which said form rollers reciprocate to carry ink to the forms, means for pressing the material to be printed against said forms, and driving mechanism for positively rotating said fountain rollers and said vibrator rollers, axially moving said vibrator rollers, reciprocating said form roller carriage and moving said means.
15. A multi-color printing press having a plurality of ink fountains adapted to be arranged in sets, a set of ink distributing rollers for each fountain set, a printing frame for receiving printing forms arranged in sets corresponding to the fountains, a form roller for each fountain set, a form roller carriage for holding the form rollers and movable forth and back so that the form rollers are carried over the distributing rollers and over the forms, means for causing selective contact between form rollers and distributing rollers and between form rollers and forms, and means for preventing contact between all of the form rollers and all of the distributing rollers when the carriage is moving in one direction and permitting contact between certain form rollers and corresponding distributing rollers when the carriage is moving in the opposite direction.
16. A multi-color printing press having a series of removable ink fountain frames, a fountain roller shaft journaled in each frame and removable therewith, a set of individually removable and adjustable ink fountains carried by each frame comprising a fountain roller for each of said fountains, said roller carried by said shaft, a type frame for carrying printing forms in sets corresponding to fountain sets, and means for selectively transferring ink from each fountain set to a corresponding set of forms.
17. A printing press as set forth in claim 16 wherein each fountain frame is adjustably carried by guideways associated with the press framework.
18. A printing press as set forth in claim 16 and having a ratchet wheel for each fountain shaft, a ratchet pawl for each wheel, a common actuator for the ratchet pawls, and a slip connection between each pawl and the actuator for facilitating the removal of any fountain frame.
- In testimony whereof I hereunto subscribed my name.
- CHARLES A. RICHARDS.
